US00D616485S

(12) **United States Design Patent**
Thixton

(10) **Patent No.:** **US D616,485 S**
(45) **Date of Patent:** **** May 25, 2010**

(54) **EYEGLASS AND EYEGLASS COMPONENTS**

(75) Inventor: **Lek Thixton**, Eastsound, WA (US)

(73) Assignee: **Eye Safety Systems, Inc.**, Ketchum, ID (US)

(**) Term: **14 Years**

(21) Appl. No.: **29/316,980**

(22) Filed: **Nov. 13, 2009**

(51) **LOC (9) Cl. 16-06**

(52) **U.S. Cl. D16/314**

(58) **Field of Classification Search** D16/101, D16/300-342; D29/109-110; D24/110.2; 351/41, 44, 51-52, 62, 158, 92, 103-123, 351/140, 153, 45-46; 2/426-432, 447-449, 2/441, 434-437, 13, 15; D21/483, 659-661

See application file for complete search history.
